UNITED STATES PATENT OFFICE.

RICHARD WHITAKER, OF NEW BRUNSWICK, NEW JERSEY, ASSIGNOR, BY DIRECT AND MESNE ASSIGNMENTS, TO BRUNSWICK REFRIGERATING COMPANY, A CORPORATION OF NEW JERSEY.

GAS-PUMP.

No. 821,563

Specification of Letters Patent.

Patented May 22, 1906.

Original application filed January 11, 1904, Serial No. 188,612. Divided and this application filed January 5, 1906, Serial No. 239,723.

To all whom it may concern:

Be it known that I, RICHARD WHITAKER, a citizen of the United States, residing at New Brunswick, county of Middlesex, State 5 of New Jersey, have invented certain new and useful Improvements in Gas-Pumps, of which the following is a specification.

This invention relates to improvements in pumps for compressing gas, such as ammonia-gas in ice-making machines, and is a division 10 of my application filed January 11, 1904, Serial No. 188,612.

The objects of the present invention are to produce a pump made of as few parts as possible and connected together by ground 15 joints, so that packing will be dispensed with.

Another object is to provide means for separating ammonia-gas which may leak by the packing-rings of the piston into the oil-chamber. 20

I attain these objects by the mechanism illustrated in the accompanying drawings, in which—

Figure 1 is a sectional view of a pump similar to that disclosed in my original application and embodying my present invention, and Fig. 2 is a modification thereof.

In both of the views like parts are designated by the same reference characters.

The casing 1 is of the general shape shown and is provided with a bearing 2, a gland 3, and packing-rings 4 for the passage of the actuating-shaft 5. A cover 6, having a bearing 7, is secured to one side of the casing 1 by 30 means of stub-bolts 8, the joint between them and the casing being ground or otherwise rendered oil-tight, so that the casing will serve as a receptacle for the lubricating-oil.

The eccentric 9 is provided with integral 40 bearing portions or stub-shafts 10, which are mounted within the bearings 2 and 7, any end play being prevented by engagement with the cover, which also holds the eccentric in position. The shaft 5 passes through the center of the eccentric and is secured in place by any suitable means, such as the key 11. By mounting the eccentric upon integral bearing portions no support is given to it by the shaft 5, the latter serving merely to impose 45 part rotary motion to the eccentric. The shaft therefor may be of smaller size than

would otherwise be necessary if the eccentric were directly supported upon it. It may be removed and a shorter or longer shaft substituted without changing the adjustment of 55 the bearings for the eccentric and it need not be so accurately alined, as would be the case if the eccentric were supported upon the shaft directly. Another advantage lies in the fact that the eccentric and supporting bearing 60 portions being cast in one piece is much cheaper than if it were keyed directly to the shaft. Furthermore, the key 11 may be made longer and applied or removed with greater facility.

The outside cover 12, dished, as shown, is applied to the cover 6 and forms, in conjunction with the cover 6, a double cover, constituting a condensing-chamber 13. The cover 12 is preferably secured in place by the same 70 set of securing-bolts as are used for the inner cover. This chamber communicates with the inside of the casing 1 by two or more small openings 14, one above and the other below the level of the oil, and by means of 75 which the oil within the chamber 13 will always be at the same height as that within the casing 1. The chamber 13 serves the purpose of a condensing-chamber and permits the escape of the ammonia-gas which 80 may leak by the packing-rings of the piston into the oil-casing 1. The escaping gas may be drawn off by means of the pipe 15 into the gas-tank and again compressed and loss of ammonia thereby prevented.

The cylinder 16 is entirely separate from the casing and is provided with a ground shoulder 17, which rests upon the upper part of the casing 1 to form a gas-tight joint. The cylinder is preferably provided with an integrally-formed water-jacket 18 and a ground upper face 19. Upon the upper face 19 is a valve support or guide having a ground upper face which rests upon a valve cap or crown similar to that disclosed in my original 95 application and in my application filed January 5, 1905, Serial No. 239,724. Means is shown in these two applications for patent for clamping the valve-guide and valve against the upper part of the cylinder, so that 100 the valve may be removed with great facility.

The piston 20 is secured to the connecting-

rod 21 by means of any suitable bearing, but preferably by that which forms the subject-matter of an application for patent filed by me on the 5th day of January, 1905, Serial No. 239,725. The connecting-rod 21 is preferably cast integral with the eccentric-strap 22.

In Fig. 2 is shown a construction having an additional water-jacket 23 for the condensing-chamber 13. This jacket may be cast integrally with the cover 12, as shown, or may be made by attaching a separate cover thereto. The water-jacket 23 preferably communicates with the jacket 18 of the cylinder by any suitable means, as by a pipe 24. Circulation of water will pass through both jackets and exhaust through the pipe 25. In the same view an improvement is illustrated by means of which one of the joints will be dispensed with and the chance of leakage thereby reduced. The cover 12 in this view is shown as bearing directly against the casing 1 and is secured thereto by the bolts 8, as before described. The inner cover 6, which carries the bearing 7, is mounted within a shoulder 26, formed upon the inner face of the cover 12 and entirely within the chamber 1. The covers 6 and 12 are secured together, as shown, by means of stub-bolts 27, entering threaded openings within the cover 12 and passing through openings in the cover 6 and being therein set up by the nuts 28, as shown.

It will be understood that the covers 6 and 12 may be first secured together and then the cover 12 with the other cover attached thereto applied to the casing 1.

Having now described my invention, what I claim, and desire to secure by Letters Patent, is—

1. A gas-pump having an oil-chamber and a removable cover and a second cover attached thereto forming a condensing-chamber, and means for removing gas from the condensing-chamber.
2. A gas-pump having an oil-chamber and a condensing-chamber communicating there-

with, the said condensing-chamber having a water-jacket.

3. In a gas-pump, having an oil-chamber and a condensing-chamber communicating therewith, the said condensing-chamber having a water-jacket communicating with the water-jacket of the pump.

4. In a gas-pump, the combination of a casing with a shaft-bearing, a cover for one side of the casing, the cover carrying the other bearing, a second cover attached to the casing-cover, forming a condensing-chamber, and a water-jacket on the condensing-chamber cover.

5. In a gas-pump, the combination with a casing, of a bearing-supporting cover, and a condensing-chamber cover, the two covers being secured together and to the casing by bolts.

6. In a gas-pump, the combination with a casing, of a condensing-chamber cover bolted thereto, and a bearing-supporting cover, bolted to the condensing-chamber cover, and entirely within the casing, so that only one joint will be made, and a water-jacket on the condensing-chamber cover, said water-jacket communicating with the water-jacket of the pump.

7. In a gas-pump, the combination with a casing, of a condensing-chamber cover bolted thereto, and having a shoulder on its inner face, and an inside cover secured to the condensing-chamber cover, and engaging with the shoulder, means for removing gas from the condensing-chamber, and a water-jacket on the condensing-chamber, said water-jacket communicating with the water-jacket of the pump.

This specification signed and witnessed this 27th day of December, 1904.

RICHARD WHITAKER.
